Daniel W. Coran, Belmont, Mass., assignor to
Raytheon Manufacturing Company, Newton,
Mass., a corporation of Delaware

Application November 13, 1951, Serial No. 17,371

Term of patent 14 years

(Cl. D26—13)

To all whom it may concern:

Be it known that I, Daniel W. Coran, a citizen of the United States, residing at Belmont, in the county of Middlesex and the Commonwealth of Massachusetts, have invented a new, original, and ornamental Design for a Control Knob, of which the following is a specification, reference being had to the accompanying drawings, forming part hereof, in which

Fig. 1 is a top plan view of a control knob, showing my new design;

Fig. 2 is a front elevation view;

Fig. 3 is a side elevation view; and

Fig. 4 is an enlarged detailed view of the knurl. I claim:

The ornamental design for a control knob, substantially as shown.

DANIEL W. CORAN.
